E. FURST.
FIRE EXTINGUISHER.
APPLICATION FILED MAY 10, 1918.

Patented Oct. 8, 1918.

UNITED STATES PATENT OFFICE.

ERNEST FURST, OF NEW YORK, N. Y.

FIRE-EXTINGUISHER.

1,281,151.

Specification of Letters Patent.

Patented Oct. 8, 1918.

Application filed May 10, 1918. Serial No. 233,665.

To all whom it may concern:

Be it known that I, ERNEST FURST, a citizen of the United States, and a resident of New York city, in the county of Bronx 5 and State of New York, have invented certain new and useful Improvements in Fire-Extinguishers, of which the following is a specification.

This invention relates to a fire extinguisher of novel construction, and more particularly to novel means for preventing the liquid contents of the extinguisher from dripping therefrom under internal pressure due to a rise in temperature, while in no 15 wise impeding the discharge of the extinguishing fluid when generated.

In the accompanying drawing:

Figure 1 is a longitudinal section of a fire extinguisher embodying my invention, and 20 Fig. 2, a side elevation thereof.

The shell 1 of the extinguisher which is shown to be of conical form is provided at its base with a head 2, having a central aperture in which is seated a flanged collar 3. 25 This collar receives one end of a foraminated cylinder 4 that projects a distance into shell 1, and is adapted to inclose a glass bottle or other breakable or pierceable container 5, the end of which engages a buffer 6. 30 Into the outer end of cylinder 4, projects an exteriorly accessible plunger 7, that passes through a cap 8, threaded on collar 3, and packed as at 9. Shell 1 is in practice, charged to a certain height with one 35 of the liquid constituents of the extinguishing fluid, such as a solution of bicarbonate of soda, while the container 5 is charged with the other constituent thereof, such as sulfuric acid. Into the liquid dips one end 40 of an outlet pipe, the other end of which leads to a nozzle 11. In case of fire, the device which is normally suspended by means of a ring or hanger 10, is grasped by 45 a handle 10, and plunger 7 is forced inward, so as to break the container, and cause the contents thereof to commingle with the contents of the shell, the extinguishing fluid thus formed being discharged through the nozzle. In practice, only part of the 50 shell 1 can be charged with the liquid, in order to leave a gas chamber, and thus there is formed within the shell, an air space 12. During a rise in temperature, the expansion of the air within this space would be apt to 55 force the liquid up within the outlet pipe above the liquid level, and out of the nozzle,

so as to form objectionable drippings, that settle on the surface of the shell. In order to overcome this objection, the following construction has been devised: The outlet 60 pipe 13 is normally submerged at its lower or receiving end within the liquid, and is here provided with a screen 14. The upper or delivery end of the pipe opens into the bulged bottom 15 of an elongated chamber 16, housed within shell 1 and resting preferably against the wall thereof. At the mouth of pipe 13, bottom 15 constitutes, or is furnished with, the seat for a ball valve 17 which is confined within chamber 16 and 65 is of such a weight that it will not become unseated by the relatively slight pressure due to fluctuations in temperature or by the floating action of the liquid, but that it will become readily unseated by the relatively 70 great pressure generated by the commingling of the chemicals.

Into the bulged head 18 of chamber 16, projects a second outlet pipe 19, which is preferably of smaller diameter than pipe 13 and connects directly with nozzle 11. This pipe extends a considerable distance into the upper portion of chamber 16, as at 20 and is here apertured and provided with a screened bottom 21.

Under ordinary or rising temperatures, valve 17 will remain seated to cut off communication between pipe 13 and chamber 16 and consequently between the contents of shell 1 and nozzle 11, thus preventing drippings. When, however, the extinguishing fluid is generated, the valve will be lifted and be forced against head 18, sidewise of projection 20, so that the apertures in the latter remain unobstructed, and the fluid is free to pass through chamber 16 and pipe 19 out of nozzle 11, the valve being of course, also unseated when the device is tilted out of its upright position during use.

In lieu of employing a fragile container, I may use a cartridge containing a gas, filled under pressure, and which upon the puncturing of the container, is discharged into the liquid, so as to form the extinguishing fluid.

For charging, the device is reversed and the solution is poured in only to a level slightly below the then uppermost screened bottom 14 of pipe 13, because were a larger charge introduced, it would run out through the nozzle (the ball valve 17 being unseated). 110 After the charge has been introduced, the device is righted, whereby the ball valve be-

comes reseated. As during charging, no liquid can flow into pipe 18, it can also not flow into chamber 16 which thus remains empty even after the shell has been righted. However, this is not a necessary feature, but it is desirable for the reason that spilling through the nozzle during transportation or when the device is installed on a ship or train is checked.

10. I claim:

1. A fire extinguisher comprising a shell adapted to receive a liquid constituent of an extinguishing fluid, a container adapted to receive a second constituent thereof, a discharge pipe that dips into said liquid constituent, and a valve controlling said pipe, said valve being adapted to remain seated under temperature fluctuations, but to become unseated by the pressure of the extinguishing fluid when generated.

2. A fire extinguisher comprising a shell adapted to receive a liquid constituent of an extinguishing fluid, an inclosed container adapted to receive a second constituent there-

of, a pair of discharge pipes, one of which is adapted to dip into said liquid constituent, a chamber intermediate said pipes, and a valve within said chamber, said valve being adapted to remain seated under temperature fluctuations, but to become unseated by the pressure of the extinguishing fluid when generated.

3. A fire extinguisher comprising a shell adapted to receive a liquid constituent of an extinguishing fluid, an inclosed container adapted to receive a second constituent thereof, a pair of discharge pipes, a chamber intermediate said pipes, one of said pipes being adapted to dip into said liquid constituent, while the second pipe extends a distance into said chamber and is perforated within the chamber, and a valve confined within the chamber and adapted to remain seated under temperature fluctuations, but to become unseated by the pressure of the extinguishing fluid when generated.

ERNEST FURST.
